OF PITTSBURGH, PENNSYLVANIA, ASSIGNORS TO GULF REFINING COMPANY, OF
PITTSBURGH, PENNSYLVANIA, A CORPORATION OF TEXAS.

PROCESS AND APPARATUS FOR CRACKING HYDROCARBON OILS.

Application filed January 15, 1921. Serial No. 437,482.

This invention relates to an improved method and apparatus for making motor fuel or gasoline by cracking hydrocarbon oils, such as the higher boiling fractions and residual oils of petroleum distillation, shale oil, etc. More particularly, it relates to improvements in the cracking of such oils in a still of the horizontal cylindrical boiler type of the class referred to in our 10 copending applications Serial Nos. 437,481 and 628,501.

When such oils are subjected to cracking in an externally heated still, serious difficulties are encountered in large-scale operations, due to the deposition of a carbonaceous solid, commonly referred to as "carbon," on the heated walls of the still. Such a deposition of "carbon" interferes with the conduction of heat into the oil, and results 20 in increased cost of gasoline-production owing to the necessity of cleaning the "carbon" from the still-walls and the loss of operating time during such cleaning operations; while the life of the still-wall is 25 comparatively short due to the rapid burn-out of the iron in contact with "carbon".

Attempts have been made to overcome the difficulties mentioned by providing stirrers in the still for agitating the oil, but such 30 stirrers are open to the objection that they require stuffing boxes which must operate against highly heated oil or hot oil vapors at high pressures.

According to the present invention, the 35 cracking operation is carried out in a still of the horizontal cylindrical boiler type, but with avoidance or substantial avoidance of objectionable deposition of "carbon" on the still walls, and with efficient circulation of the oil in the still, without the provision of mechanical stirrers.

In carrying out the invention, we provide, in a horizontal boiler type of still, a plurality of transverse vertically arranged 45 baffles, extending across the still and spaced apart from each other and from the bottom of the still, and dividing the oil into a series of transverse bodies, and we provide for the introduction of jets of gas between certain of the baffles so as to bring about an effective circulation of the oil, upwardly 50 between certain of the baffles and downwardly between certain of the other baffles.

The alternate spaces between the baffles, into which the gas is introduced and through 55 which the oil is caused to flow upwardly, may be sub-divided, by partitions, into a series of spaces, arranged as a transverse series, and the gas introduced into each of the individual spaces of the series. The 60 baffles extend to near the heated bottom of the still and upwardly to near the top of the body of oil therein, or to a sufficient height so that the currents of gas introduced therebetween will bring about effective 65 circulation of the oil over the heated bottom of the still, and so that the formation of an objectionable "dead layer" of oil on the heated bottom of the still is 70 avoided. The resulting circulation of the oil in a series of circuits or cycles along the length of the still brings about effective and uniform heating and circulation of the entire body of oil in the still and promotes the desired cracking operation.

The still itself, as well as the construction, arrangement and number of transverse baffles, can be varied, and the still can be operated intermittently, upon successive 75 charges of oil, or continuously over long periods of time with more or less continuous introduction of further amounts of oil and continuous or periodical removal of residue.

The invention will be further illustrated 80 and described in connection with the accompanying drawing which shows, in a somewhat conventional and diagrammatic manner, one form of apparatus embodying the invention and adapted for the practice of 85 the process of the invention.

In the accompanying drawings—

Figs. 1 and 2 show one embodiment of the apparatus in vertical transverse section, and vertical longitudinal section, respectively, Fig. 1 being a section on line 1—1 of Fig. 2 and Fig. 2 being a section on line 2—2 of Fig. 1;

Fig. 3 shows a modified form of apparatus, in transverse section on line 3—3 90 of Fig. 4;

Fig. 4 is a partial, vertical, longitudinal section on line 4—4 of Fig. 3; and

Fig. 5 is a partial, vertical, longitudinal section of a further modified construction 105 of the apparatus.

In the different figures of the drawings similar parts are indicated by the same reference numerals with the letters "a" or "b" appended thereto in Figs. 3, 4 and 5.

5 In the apparatus illustrated in Figs. 1 and 2, the still 1 is an ordinary horizontal cylindrical boiler type of still with its bottom arranged in a furnace chamber 2 so that it will be heated by direct heat or by 10 products of combustion. The furnace structure and the particular method of heating can, of course, be varied. The still is provided with the usual oil inlet pipe 3 from which oil is supplied in any suitably 15 regulated manner, with the vapor outlet 4 from which the vapors are led successively to a dephlegmator and condenser (not shown), and the residue outlet 5. It will be understood that the oil can be supplied 20 in a more or less continuous manner, and the oil supply regulated automatically in accordance with the desired level to be maintained in the still, where the operation is to be carried out in a continuous manner. So also, the residue can be withdrawn 25 periodically or continuously. A particularly advantageous arrangement of the oil inlet and residue outlet is to have these at opposite ends of the still, for reasons hereinafter pointed out.

Arranged within the still are a plurality of transversely arranged directing baffles 6 which may vary in shape, size and arrangement, but which are shown as arranged in 30 pairs. In the alternate spaces between the baffles are arranged means for introducing gaseous currents. The means illustrated are a series of transverse, perforated pipes 7, each connected with a supply pipe or manifold 8 to which the compressed gas is in turn supplied through the supply pipe 9 having a suitable regulating valve 10 therein.

45 In the apparatus of Figs. 3 and 4, the transverse directing baffles are inclined and made narrower at their upper ends in order to reduce the speed of gas separation and assist in maintaining the foam in the still. In the apparatus of Fig. 5 the directing baffles are curved and nearer together near their central or intermediate portion, giving a section similar in appearance to that of a Venturi tube.

55 As above stated, the transverse spaces through which the oil is circulated upwardly by the introduction of the gaseous currents (acting on the "air-lift" principle), may be sub-divided by partitions into a series of small spaces, into each of which 60 the gas is introduced to bring about the "air-lift" circulation. Such an arrangement is illustrated in Figs. 3 and 4, and also in Fig. 5, in which a series of partitions 12^a and 12^b respectively, are provided, forming a series of transversely arranged spaces. Each

of the spaces thus formed is provided with one or more gas jets, shown as short branch pipes 13^a in Figs. 3 and 4, extending upwardly from the gas supply pipes 7^a and 8^a. The baffles 14 near the side walls of the still 70 may be somewhat curved to conform to the contour of the still walls and leave a space between them and the still walls which is not materially greater in cross section at the top than at the bottom. So also, the end 75 jet pipes 15, through which the gas jets are introduced, may be arranged to discharge outwardly and upwardly, as shown, in order to promote the circulation of the oil through these outer individual spaces. The intermediate spaces between the transverse baffles, through which the oil flows downwardly, are left free and unobstructed, in the apparatus 80 illustrated in Figs. 3 and 4.

In Fig. 5 the supply pipe 8^b for the gas 85 is so arranged that the gas jets discharge therefrom, for example, through branch tubes 16, arranged at the narrowest portion of the space between the baffles, to increase the resulting jetting action and thereby pro- 90 mote the circulation.

In the operation of the apparatus, the oil is maintained therein at a suitable level by suitable automatic or other regulating means (not shown), and the still is heated from below in much the usual way. Currents of gas are forced in through the various branch pipes and rise upwardly in the oil between the baffles, thus causing an upward circulation of the oil between the baffles and a 100 downward flow of oil between the alternate pairs of baffles which have no gas jets between them. Circulation is thus brought about in a series of paths or cycles, each path or cycle involving the downward circulation 105 of the oil between the baffles, the flow of the oil underneath the lower edges of the baffles, and the upward flow of the oil in the alternate spaces between the baffles due to the gas introduced therebetween, acting on the 110 "air-lift" principle. The oil is thus kept effectively agitated and circulated, while the bottom of the still which is subjected to the direct heat of the furnace chamber is kept substantially free from objectionable "car- 115 bon" deposit by the scouring action of the rapidly circulating oil which forms scouring eddies in its flow beneath the lower edges of the baffles. The entire body of oil in the still is thus broken up into a series of smaller 120 circulating bodies which circulate in the manner above described, in a series of cycles around the vertical transverse baffles.

When the oil inlet is at one end of the still and the residue outlet is at the other, it will be seen that the oil flowing through the still from the inlet to the residue outlet tends to pass progressively along the still where it is recirculated in the successive cycles. By properly proportioning the height of the 130

baffles with respect to the oil level in the still, the oil can be given a progressive treatment so that a portion thereof will be cracked while the oil is near the inlet end of the still, and progressive cracking will take place as the oil progresses towards the residue discharge end of the still and is caused to undergo recirculation in the series of paths around the successive baffles. The circulating of oil tends to scour off any carbon deposit that may form on the heated surfaces and its scouring action is promoted by the carbon that may be carried in suspension in the oil during its circulation. Thus, even if a considerable accumulation of carbon is present in the oil near the residue discharge end of the still, the effective breaking up of the oil into a series of successive circulating bodies, and the rapid and effective circulation, keep the carbon in suspension and prevent it from forming objectionable carbon deposits on the heated bottom of the still.

The gas which is used for bringing about the circulation of the oil in the manner described may advantageously be a part of the fixed gases or of the vapors produced by the cracking operation itself, but other appropriate gas can be used, such as natural gas or casing-head gas, or other gaseous material such as steam, which has no objectionable effect upon the cracking operation. The fixed gas from the condenser may thus be returned to the still for bringing about the circulation, or a part of the hot gases and admixed vapors may be taken from the vapor line leading to the final condenser and returned to the still for this purpose. If the condenser is operated under the same pressure as the still, as in the preferred practice, the fixed gas can be withdrawn at this pressure and recirculated so that the amount of further compression necessary is correspondingly reduced. So also, if a part of the hot gases and vapors are taken off at some point between the still and the final condenser, and reintroduced into the still, their heat will be to a considerable extent conserved. The gas that is introduced into the still can itself be preheated to avoid the cooling effect that might otherwise be objectionable.

The introduction of the currents of gas not only serves to insure effective agitation and circulation of the oil, but it promotes the regular removal of the lower boiling constituents resulting from the cracking operation as they are formed, and prevents their remaining in the still for prolonged periods of time to undergo further decomposition. The gases and vapors produced by the cracking operation will be diluted by the gases separately introduced and the entire mixture will be passed through the dephlegmator and vapor pipe to the condenser or condensers for the removal of

condensable constituents. The excess gas can be discharged in any suitable manner. If a part of this gas is to be used for reintroduction into the still, it can be passed through a pump or gas booster and brought to the necessary pressure for its reintroduction. It will be understood that the pressure of the gas can be varied, and that the rapidity of circulation and violence of agitation of the oil can be to a certain extent controlled by the rate and pressure of the gas introduced, as well as by the arrangement of the gas inlet pipes and of the baffles in the still.

In carrying out the process, it will be understood that the oil is raised into that range of temperature in which cracking occurs, and maintained at the appropriate temperature and pressure for the cracking operation. The rapid and efficient circulation of the oil and the breaking up of the oil body into a series of locally circulated portions, tends to prevent any local objectionable overheating of any portion of the oil and permits the uniformity of heating of the entire body of oil so that the operation can be carried out with the production of considerable amounts of naphtha and gasoline and relatively little gas and carbon, and without objectionable local overheating of the oil to the still higher temperature at which much gas and "carbon" are formed. The continuous and effective circulation of the oil keeps the entire body of oil in the desired temperature range and gives a resulting cracking operation of a more uniform character. The oil which becomes hot by its circulation in contact with the heated bottom of the still is continuously swept or scoured off so that the formation of a "dead-layer" of oil is prevented, with resulting prevention of the heating of such a layer to objectionably high temperatures, and hence with substantial avoidance of objectionable "carbon" deposit. Much more effective heat transfer through the heated bottom of the still is thus made possible, while the still bottom itself is protected by the absence of any objectionable layer of "carbon" deposited thereon such as is common in horizontal boiler stills as they are now operated.

It will be seen that the entire circulation of the oil is brought about by the arrangement of the baffles and the introduction of the gaseous currents, acting on the air-lift principle, so that mechanical agitators and moving mechanism are avoided, with avoidance of stuffing boxes, so that all connections of the still may be welded and made gas-tight. The circulation of the oil is nevertheless a positive circulation and this circulation can be effected with a sufficient velocity to break up or prevent the "dead-layer" of oil which has heretofore been the

chief cause of "carbon" trouble and deposit.

In illustrating the various forms of apparatus in the accompanying drawings, we have omitted the heat insulation or lagging of the still, connecting pipes, etc., but it will be understood that, in practice, suitable heat insulation will be provided to avoid objectionable losses from all exposed parts of the still and of the system which become heated.

In practice it will be understood that the still will also be provided with suitable pressure and temperature indicating devices, as well as suitably regulated oil supply means, which may be automatic, for maintaining a regulable oil supply and oil level in the still and suitable means for supplying the gas in sufficient amount and under an appropriate pressure. Temperature indicating devices can thus be provided between successive or alternate baffles, along the length of the still, so that the operator can tell the temperature of the oil circulating in different parts of the still and be warned of any irregularity of operation. The condenser (not shown) may be of any suitable construction, and, in the preferred practice, is in open communication with the still and operated at the still pressure, with the regulating valve in the line beyond the condenser. The condenser can, however, be operated at a lower pressure, and a suitable regulating valve provided between the still and condenser for this purpose. A regulated cracking pressure of, for example, between 60 and 500 lbs. per square inch, and preferably in the neighborhood of 75 to 150 lbs. per square inch, can thus be maintained, the temperature and pressure varying somewhat with the nature of the oil to be cracked and the products desired.

The oil feed to the still may be preheated to a greater or less extent, and, for this purpose, a part of the necessary heat can be supplied by means of a heat interchanger (not shown) through which the still "bottoms" are discharged; while a part of the preheating may be effected by bringing the oil into heat-interchanging relation with the hot vapors from the still. The oil feed can thus be passed through the condenser for the vapors from the still, or through one or more of the series of such condensers where such a series is used for cooling and condensing the vapors. The preheating effect thus secured may be supplemented, if desired, by further preheating of the oil feed in any suitable manner, and the oil can advantageously be preheated to such a degree as to vaporize and remove any water present therein before the oil is introduced into the still.

It will thus be seen that the present invention provides for the carrying out of the cracking operation with effective circulation

and recirculation of the oil in a particularly advantageous manner which promotes and insures uniformity of circulation and of heating of the entire body of oil as well as the prevention or substantial prevention of objectionable carbon deposit upon the heated still bottom. The erosive action of the oil upon deposits on the still bottom can be further increased by adding to the oil a little sand, fine gravel or metal filings, which are circulated with the oil and assist in preventing and removing objectionable carbon deposition.

In referring to the cracking of "oil" in the present specification and claims, we intend to include the treatment of various hydrocarbon oils, and more particularly the treatment of higher boiling fractions and residual oils of petroleum or shale oil distillation, for the production of motor fuel or gasoline; but other oils, such as lignite or coal tar, or tar oils, etc., can be similarly treated; and we include all such materials within the term "oil", as used in the accompanying claims.

It is to be understood that a plurality of stills of the designs disclosed in this specification may be arranged in series and the oil to be cracked passed through them consecutively.

We claim:

1. The method of cracking oils in a horizontally arranged still, which comprises heating a body of the oil therein by external heat to the cracking temperature under pressure, subdividing the main body of oil in the still into a series of transversely arranged smaller bodies communicating with each other at their upper and lower ends, introducing the oil to be cracked at one end of the still and withdrawing the residue from the other, and maintaining effective circulation of the oil in the said transversely arranged bodies and along the heated bottom of the still by the introduction of gaseous currents, acting on the "air-lift" principle, near the lower ends of the sub-divided smaller bodies.

2. An apparatus for cracking oils, comprising a horizontally arranged and externally heated still having a series of vertically arranged transverse baffles therein spaced apart from the still bottom and means for introducing gaseous currents into the alternate spaces between the baffles, whereby circulation of the oil is effected around the said baffles and over the bottom of the still.

3. An apparatus for cracking oils comprising a horizontally arranged and externally heated still having an inlet at one end and a residue outlet at the other, a series of transversely arranged baffles in the still spaced away from the bottom thereof, and means for introducing gaseous currents between some but not all of said baffles to

bring about effective circulation of the oil in the still.

4. An apparatus for cracking oil comprising a horizontally arranged and externally heated still having an oil inlet at one end and a residue outlet at the other, a series of vertically arranged transverse baffles within the still spaced apart from the still bottom,

and means for introducing upwardly flowing gaseous currents into the alternate spaces ¹⁰ between said baffles.

In testimony whereof we affix our signatures.
